UNITED STATES PATENT OFFICE.

WILLIAM EDWARD ANDRÉE, OF CHICAGO, ILLINOIS, ASSIGNOR TO THE AMERICAN LAUNDRY MACHINERY COMPANY, OF CINCINNATI, OHIO, A CORPORATION OF OHIO.

PRESSING-MACHINE.

1,369,769.

Specification of Letters Patent.

Patented Mar. 1, 1921.

Application filed May 18, 1917. Serial No. 169,474.

To all whom it may concern:

Be it known that I, WILLIAM EDWARD ANDRÉE, a citizen of the United States, residing at Chicago, in the county of Cook 5 and State of Illinois, have invented certain new and useful Improvements in Pressing-Machines, of which the following is a specification.

This invention relates to pressing machines such as are used for pressing garments, cloth, woven fabrics or the like. The object of the invention is to provide an improved pressing machine embodying relatively movable bucks or pressing members 10 suitably padded, as is usual, together with means for applying moisture to the garment to improve the pressing operation, and means for quickly drying the garments being pressed and the pads of the pressing 15 members, to thereby enable garments to be pressed and dried more quickly, to keep the pads dry and efficient, and to avoid spotting or injuring the garments being pressed by moisture in the pads. A further object of 20 the invention is to provide an improved pressing machine in which the garments being pressed and the pads are dried by a current of air passed therethrough, preferably under pressure, and said air being 25 heated to produce maximum drying effects. 30

Further objects of the invention are in part obvious and in part will appear more in detail hereinafter.

The invention comprises the pressing machine, hereinafter described and claimed.

In the drawings, which represent one embodiment of the invention, Figure 1 is a side elevation, showing the press closed; Fig. 2 is a front elevation, partly broken 40 out and in section; and Fig. 3 is a detail section, showing the steaming device in the stationary pressing member.

The pressing machine shown in the drawings comprises a suitable frame 1 having a front standard 2 supporting a stationary lower pressing member or buck 3, and a rear standard 4 to which is pivoted a swinging arm or lever 5 supporting the movable upper pressing member or head 6 for coöperation with buck 3 in the usual manner. 45 The shape or configuration of the head or buck to accommodate garments of different kinds may obviously be varied within wide limits. The head is normally held elevated 50 by a spring 7 and is depressed into pressing 55

relation with the buck by operation of a foot treadle 8 connected by a link 9 to a lever 10 which is connected by a link 11 to operate two toggle links 12, 13 indicates a release treadle having an arm 14 extending 60 under the treadle 8 for elevating the same to break the toggle.

The upper pressing member is heated by steam admitted to its hollow heating chamber 15 through a supply pipe 16. Its lower 65 face is smooth and uninterrupted, but is covered with the usual padding or press cloth indicated at 17.

The buck 3 is of complementary form to the head 6, its upper surface being likewise 70 provided with padding 18 lying over the perforated plate 19, the perforations in which communicate with a hollow chamber 20 extending over substantially the entire area of the buck. Beneath the plate 19 is a 75 horizontal wall 21, dividing the space within the buck into two chambers, one the chamber 20 before referred to, and the other a chamber 22 communicating with a suitable source of heating medium, by a pipe 80 23. The garments to be pressed may be moistened in any suitable manner, such as by steam supplied to the upper surface of the garment or from the lower buck, as desired. As illustrated, the horizontal wall 21 85 is provided with passages 24 therethrough controlled by a valve 25 seating upwardly and held to its seat by the spring 26. The valve stem 27 passes down through a stuffing box 28 to a lever 29, by depressing which 90 the valve may be opened to permit steam to flow from the live steam chamber 22 through passages 24 to chamber 20, and thence through the perforations in plate 19 and through the padding 18 to the garment. 95 When lever 29 is released valve 25 closes and cuts off the supply of steam to chamber 20.

Chamber 20 not only is the steaming chamber in the buck, but also is the chamber through which air is supplied to the pads 100 for drying the same and for also drying the article being pressed. For this purpose chamber 20 communicates by way of a passage 30 with a pipe 31 communicating with a suitable source of air supply, such as with 105 the discharge side of a suitable fan or blower 32. Passage 30 has its upper end formed as a valve seat to receive a valve 33 whose stem 34 passes out through an L 35 in the pipe 31, outside of which it is provided 110

with a valve seating spring 36 capable of holding the valve to its seat against the incoming air pressure. The valve may be lifted from its seat in any suitable manner, 5 such as by suitable mechanism connected to its valve stem. This may be an independent connection to a separate lever, enabling the valve to be opened at any time, but is shown as connected to the release treadle 13, which 10 is provided with an arm 37, connected by a link 38 to one arm of a bell crank lever 39, the other arm of which is connected through a yielding spring 40 to the valve stem. Consequently, whenever the release treadle is 15 depressed to open the press the air pressure is turned into the chamber 20. This will occur simultaneously with the opening movement of the press and at a time when the steam valve 25 is closed. The air pressure 20 may be held on as long as desired.

With the arrangement described garments may be pressed and dried more quickly than with presses as heretofore constructed. The buck is heated by the live steam constantly 25 present in chamber 22. Therefore, the air supply for drying the garments passes through a heated chamber and its temperature is elevated considerably above the atmospheric. This materially improves the 30 ability of the moving air to absorb moisture from the padding of garments thereon. Moreover, the air pressure has a distinct advantage over suction or vacuum, as usually employed, in that it keeps the padding loose 35 and fluffy, so that it is not so liable to mat down. The pads are always substantially dry, as a result of which the press may be used for pressing garments which otherwise would be spotted or damaged by the moisture 40 of the pads. Moreover the passage of hot air through the padding maintains the pad in a hot condition, as distinguished from the cooling of said pad which occurs

when cold or atmospheric air is drawn down through the pad, as where a vacuum is employed. Other advantages of the invention will be apparent to those skilled in the art.

What I claim is:—

1. A pressing machine, comprising relatively movable coöperating upper and lower pressing members, one of which is provided with a foraminous pressing plate forming one wall of a shallow chamber, the opposite wall of said chamber forming a partition 45 between said chamber and a second chamber, means for supplying steam to said second chamber, means for supplying compressed air to said first chamber, and means controlling the flow of steam from the second to the first chamber.

2. A pressing machine, comprising relatively movable coöperating upper and lower pressing members, the lower pressing member being hollow and provided with an inner horizontal wall forming a partition between a lower and a shallow upper chamber therein, a foraminous pressing plate 65 near to and parallel with said partition and forming the upper wall of the shallow upper chamber, means for maintaining a supply of steam in the lower chamber to heat the lower pressing member, valve means controlling the flow of steam from the heating chamber to the upper chamber and 70 thence through the foraminous plate for moistening the garment, and means for producing flow of air to the upper chamber and thence through the foraminous plate for 75 drying the garment.

In testimony whereof I affix my signature in presence of two witnesses.

WILLIAM EDWARD ANDRÉE.
